UNITED STATES PATENT OFFICE

JOHN E. VAN DALL, OF COVINGTON, OKLAHOMA

WASHING APPARATUS

Application filed December 12, 1928. Serial No. 325,599.

This invention relates to a structure which may be conveniently and broadly defined as a washing apparatus for different species of granular material, and it has more particular reference to a novel machine which is especially, but not necessarily, adapted and designed for washing drill cuttings produced when drilling oil and gas wells.

More precisely described, the invention has reference to a practicable machine which is especially useful and efficient for washing samples of earth, rock and sand collected from different strata of materials encountered at different depths in well drilling operations.

Samples of this character, as is well known, are useful to geologists and company officials who are able to obtain valuable information produced from exacting analysis of the soil and sand formations encountered at varying levels.

These cuttings are collected and saved for experimentation and study. Before a proper test or analysis can be made by the geologist, it is usually necessary to wash and dry the cutting. This involves a lengthy and tedious task, is laborious, wasteful and consumes much valuable time.

It is the purpose of this invention to provide a properly organized structure forming what is believed to be a mechanical achievement in the art, and which is capable of fulfilling the requirements of an apparatus of this class in an efficient and satisfactory manner.

The particular details and their relative association and arrangement will become more readily apparent from the following description and drawings.

In the drawings:

Figure 1 is a view in section and elevation of a washing machine or apparatus constructed in accordance with the present invention.

Figure 2 is a longitudinal sectional view through a sectional rack, constituting a permanent factor of the invention.

Figure 3 is a top plan view of the rack.

Figure 4 is an elevational view of the ro-

tating shaft to which the rack is fastened for operation.

Figure 5 is a sectional view through one of the sample boxes or containers.

Figure 6 is a top plan view of the same. 55

Figure 7 is a fragmentary view of a portion of the sections of the rack.

In the drawings in Figure 1, the reference numeral 8 designates a metal tank of appropriate proportion which is adapted to be filled with water. The normal level of the water is as shown in this figure. Thus under normal operating conditions the tank is half filled with water. The tank is supported on appropriate legs 9 and is provided with a water drain. The drain embodies a pipe 10 leading to a suitable source of deposit having a valve 11 connected with a nipple 12 extending up through an appropriate fitting into the interior of the tank 79 as shown at 13. This provides a slight elevation for the upper end of the nipple causing it to assume a position above the normally collected waste sediment which accumulates in the bottom of the tank. This waste material may be discharged through a drain neck 14 provided with a removable plug 15. Supported on one side of the tank is a bearing bracket 16 for a shaft 17 which is connected with a suitable drive, for instance an electric motor (not shown). This shaft is provided with a beveled gear 18 which meshes with a complementary bevel gear 19 on one end of the operating shaft 20 within the tank. This shaft 20 terminates in journals 21 and 22 mounted for rotation in suitable water tight bearings. The shaft carries the novel rack structure 23.

As before stated, the rack is of sectional construction and embodies upper and lower sections clamped or otherwise fastened together. The upper section embodies a frame 24 divided by transverse and longitudinal bar members 25 and 26, respectively, into a plurality of cells. This frame 24 carries a plurality of spaced parallel transversely extending retaining rods 27. The lower section also embodies an identical frame 28 whose portions match the corresponding portions of the upper frame, thus allow- 106

ing the cell forming portions to come into proper alinement with each other.

The frame 28 also carries arch shaped retaining rod members 29. This sectional cellular rack is adapted to contain and hold in proper place a multiplicity of sample containers. Each container is in the form of a box 30 having a screen bottom 31 as shown in Figure 5, and a removable screen cover 32. The boxes are smaller in proportion than the cellular openings in the rack structure into which they are placed as shown in Figure 2. However, the bars 27 and 28 firmly engage the top and bottom of the boxes in the manner to prevent undue play. Incidentally this "play" is purposely intended to allow sufficient shifting of the boxes during the turning motion of the rack to produce a desired agitation of the formation material in the boxes.

In practice these sample containers are of generally rectangular form, and they are individually numbered so that they may be readily distinguished. Consequently in carrying out the washing operation, it is necessary to keep track of the different samples as they are collected. Then the containers are placed in the lower section of the rack and when the rack is filled the top section is clamped thereon by bolts or the like 34, preferably arranged at the corners of the rack structure. This keeps the containers properly assembled and prevents them from falling out during the rotary motion of the rack as it splashes through the water.

As before stated, the tank is filled about one half full of water, and the motor is started, the result being that the entire rack structure with the sample container is carried through the water. This requires but a few minutes and the sixteen or more sample boxes are then ready to be removed. After removal they are emptied into drying pans having numbers corresponding to the containers, and then placed in an oven to dry. Hence the operator has washed sixteen or more samples thoroughly in less time than he could possibly wash one with the old placer method.

A careful consideration of the description in conjunction with the drawings will enable the reader to obtain a clear comprehension of the compactness and convenience, the expediency and efficiency of this structure for accomplishing the desired result. Although the structure is especially adapted for washing different formations collected for sample taking purposes, it is understood that it may well be used for washing various species of granular materials.

Minor changes in size, shape and rearrangement of parts coming within the field of invention may be resorted to in actual practice if desired.

Having thus described the invention, what I claim as new and desire to secure by Letters Patent is:—

1. In a washing machine of the character described including a tank; a rack supported for gyratory movement within the tank, said rack being divided into a pair of sections, one of said sections being adapted to support a receptacle, the other section being adapted to retain the receptacle against the first mentioned section.

2. In a washing apparatus of the character described including a tank, a pair of superposed frames, a supporting shaft having its ends cranked and journaled in said tank, said frames mounted on said shaft, and means for rotating said shaft, whereby a gyratory movement is imparted to the frames within the tank.

In testimony whereof I affix my signature.

JOHN E. VAN DALL.
